CLAIM

The ornamental design for a watch, as shown and described.

DESCRIPTION

FIG. 1 is a perspective view of a watch showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top side elevational view thereof; and,

FIG. 7 is a bottom side elevational view thereof.

The dashed lines in FIGS. 1 to 7 show portions of the watch that form no part of the claimed design.

1 Claim, 7 Drawing Sheets(56)
